Letters Patent

The Schedule referred to in these Letters Patent and making part of the same, containing a description in the words of the said William B. Kimball, Abel Percy and Franklin Spalding themselves of their improvement in a Machine for dressing hoops for Barrels -

To all, whom it may concern

Be it known, that we, William B. Kimball, Abel Percy and Franklin Spalding of Peterborough in the county of Hillsborough and state of New Hampshire have jointly invented a new and improved machine for the purpose of dressing hoops for barrels, and we do hereby declare that the following is a full and exact description thereof, reference being had to the drawing which accompany and make part of this specification. The hoop poles or other stuff from which hoops for barrels and other vessels are to be made, are after being split out to be dressed by means of revolving cutters, the thickness to be given to them being regulated by means of a gauge adapted thereto. A is the cutter wheel attached to the shaft or mandrel B which may receive its revolving motion by means of whirles and a band as represented in the drawing or in any other convenient way. The cutters C C are fixed on their places by means of screws, their cutting edge being rounded on the face of the wheel corresponding thereto, we usually employ four cutters, but this number may be varied according to the diameter of the cutter wheel, and the velocity with which it is made to revolve. If it is preferred the cutters may be made to operate from the edge or periphery of the wheel instead of upon its face, the other parts of the machine being in this case so varied as to adapt them to this construction, we however prefer the cutting upon the face, as the cutter wheel may then be small, and the ^{upper} surface is perfectly flat. D is a roller forming a part of the gauge and against this roller bears the outside of the hoop, whilst the inside is dressed. The edge of the hoop is sustained upon a metal rim E in front of the cutter wheel. The adjusting screw F

speaks upon the gauge moving when necessary to regulate the distance of the lower D from the cutter and consequently to determine the thickness of the hoop. As there are knobs and other descriptive parts, frequently found upon hoop poles, and it is necessary on such parts to give additional thickness to the hoop, the gauge is made capable of receding at the will of the operator, in order to adapt it to these purposes. The lever by being moved by means of its handle, the inclined slide to draw the gauge back, the spring of causing it to resume its place when the hand is removed. The dotted lines represent distinctly the manner in which the part operates. We have thus fully described the construction of our machine in the form which we intend usually to give back, but in so doing we not mean to confine ourselves precisely to the mode of arranging the individual parts as we have represented them, as there may be considerable variance without altering the general principle upon which the machine operates. The door example, the arrangement of the lower D slide may be altered in different ways while the same end will be attained, we do not therefore claim the individual parts of this machine, as they have all been used under other combinations and for other purposes, but what we do claim as our invention is the construction of an instrument for dressing hoops made and operating substantially in the manner herein set forth, having a revolving cutter-wheel, a sliding gauge and the auxiliary appendages which give to it that character by which it is distinguished from other machines for the same purpose.
